DESIGN FOR A REAR VIEW MIRROR

Fred J. Aves, West Los Angeles, Calif.

Application September 9, 1948, Serial No. 148,512

Term of patent 14 years

(Cl. D14—6)

To all whom it may concern:

Be it known that I, Fred J. Aves, a citizen of the United States, residing at West Los Angeles, in the county of Los Angeles, in the State of California, have invented a new, original, and ornamental Design for a Rear View Mirror, of which the following is a specification, reference being had to the accompanying drawings, forming a part thereof, and wherein:

Fig. 1 is a front view of a rear view mirror embodying my invention;

Fig. 2 is a rear view of the same;

Fig. 3 is a plan view of the same; and

Fig. 4 is an end view of the same.

I claim:

The ornamental design for a rear view mirror, as shown.

FRED J. AVES.
